UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A SPOON-HANDLE, &c.

SPECIFICATION forming part of Design No. 25,559, dated June 2, 1896.

Application filed April 30, 1896. Serial No. 589,779. Term of patent 7 years.

To all whom it may concern:

Be it known that I, CHARLES OSBORNE, a citizen of the United States, residing in the city of New York and county and State of New York, have invented and produced a certain new and original Design for a Handle for Spoons and Similar Articles, of which the following is a specification, reference being had to the accompanying drawings, forming part thereof.

Figure 1 is a face view of the obverse, and Fig. 2 is a corresponding view showing the reverse, side of the handle.

The leading features of my design are the violin-shaped head, the fan-like ornament forming the upper portion thereof, and the cluster of blossoms bordered by leaves forming the lower part, and the molded shank swelled at intervals and ornamented with foliated scrolls and blossoms, all in relief. The fan-like ornament is composed of outwardly-curved "gadroons" diverging from a scroll-bordered plain panel surmounting the gracefully-curved foliated ornaments inclosing a cluster of blossoms and forming the lower portion of the head. The shank is beaded or molded in longitudinally-extending stems and is swelled outwardly at two points, bearing a single cinquefoil blossom in the center of the upper and two in the next. Another swell below is made up of small gadroons spreading in each direction from beneath a single similar blossom. From this point the shank widens on curved lines to join the bowl, 35 prongs, or blade. The reverse is similarly

but less elaborately ornamented. The plain panel in the head is smaller, the blossoms are omitted from the shank excepting at the lowermost swell, and the long stems or beads extend in practically unbroken lines to the foliated ornaments inclosing the cluster of open flowers in the lower part of the head. A curled leaf and tendril rises from the cluster on each face, and the scrolls bordering the panels terminate in similar ornaments.

45

The gadroon motive—the stem terminating in an enlargement or drop—is conspicuous in all parts of the handle. The stems, the scrolls, and the leaves also are all characterized by that form.

50

The design is intended to apply to all the various articles comprising the class of table flat-ware.

I claim—

1. In a design for a handle for spoons or similar articles, the obverse as herein shown and described.
2. In a design for a handle for spoons or similar articles, the reverse as herein shown and described.
3. The design for a handle for spoons or similar articles herein shown and described.

55

In testimony that I claim the invention above set forth I affix my signature in presence of two witnesses.

CHARLES OSBORNE.
